(57) **CLAIM**

The ornamental design for a display screen or portion thereof with animated graphical user interface, as shown and described.

DESCRIPTION

FIG. 1 is a front view of a display screen or portion thereof with animated graphical user interface showing a first image in a sequence according to the claimed design;

FIG. 2 is a front view of a display screen or portion thereof with animated graphical user interface showing a second image in a sequence according to the claimed design;

FIG. 3 is a front view of a display screen or portion thereof with animated graphical user interface showing a third image in a sequence according to the claimed design;

FIG. 4 is a front view of a display screen or portion thereof with animated graphical user interface showing a fourth image in a sequence according to the claimed design;

FIG. 5 is a front view of a display screen or portion thereof with animated graphical user interface showing a fifth image in a sequence according to the claimed design; and,

FIG. 6 is a front view of a display screen or portion thereof with animated graphical user interface showing a sixth image in a sequence according to the claimed design; and The appearance of the transitional image sequentially transitions between the images shown in FIGS. 1-6. The process or period in which one image transitions into another forms no part of the claimed design.

The outermost broken lines in the figures show a display screen or portion thereof, and form no part of the claimed design. The remaining broken lines show portions of the graphical user interface and form no part of the claimed design.

The display screen portions that are shown in the figures share a common center point.
